CLAIM

The ornamental design for an espresso distribution tool, as shown and described.

DESCRIPTION

FIG. 1 is a front, right and top perspective view of an espresso distribution tool, showing my new design;
FIG. 2 is a rear, left and bottom perspective view thereof;
FIG. 3 is another rear, left and bottom perspective view thereof;

FIG. 4 is a front view thereof;

FIG. 5 is a rear view thereof;

FIG. 6 is a left side elevation view thereof;

FIG. 7 is a right side elevation view thereof;

FIG. 8 is a top plan view thereof;

FIG. 9 is a bottom plan view thereof; and,

FIG. 10 is an exploded front, right and top perspective view thereof.

The broken lines in the drawings depict portions of the espresso distribution tool that form no part of the claimed design.

1 Claim, 10 Drawing Sheets
